UNITED STATES PATENT OFFICE.

THOMAS P. BROOKE, OF CHICAGO, ILLINOIS, ASSIGNOR TO THE BROOKE AIRCRAFT COMPANY, A CORPORATION OF DELAWARE.

AEROPLANE AND WING THEREFOR.

1,325,137.

Specification of Letters Patent. Patented Dec. 16, 1919.

Application filed March 10, 1917. Serial No. 153,801.

To all whom it may concern:

Be it known that I, THOMAS P. BROOKE, a citizen of the United States, residing at Chicago, in the county of Cook and State 5 of Illinois, have invented certain new and useful Improvements in Aeroplanes and Wings Therefor, and one of the objects of the present invention is to improve, simplify, and strengthen the construction of 10 the wing, with a view to increasing to a maximum its efficiency, as well as the directional stability and safety thereof, and at the same time develop in the wings inherent tractor force of soaring birds, where- 15 by the wing will have an upward and forward pull while in flight, thereby reducing to a minimum the power necessary to propel the machine.

A further object is to provide improved 20 means for overcoming excessive dangerous oscillation of the machine, and for preventing the upsetting thereof by wind pressure, while in flight.

To the attainment of these ends and the 25 accomplishment of other new and useful objects as will appear, the invention consists in the features of novelty in substantially the construction, combination and arrangement of the several parts hereinafter 30 more fully described and claimed and shown in the accompanying drawings illustrating the invention and in which:

Figure 1 is a top plan view of an improved machine of this character, constructed in accordance with the principles 35 of this invention.

Fig. 2 is a side view.

Fig. 3 is a vertical sectional view taken on line 3—3, Fig. 1.

Fig. 4 is a diagrammatic view of the wing.

Fig. 5 is a horizontal sectional view taken on line 5—5, Fig. 6.

Fig. 6 is a vertical sectional view taken 45 on line 6—6, Fig. 5.

Fig. 7 is a detail sectional view on line 7—7, Fig. 6.

Referring more particularly to the drawings and in the present exemplification of 50 this invention, the numeral 10 designates generally a body or supporting structure of the machine. Projecting laterally from opposite sides of the body are planes or wings,

designated generally by the reference numeral 11 in Fig. 1, and these planes are 55 arranged one above the other on opposite sides of the machine and supported by suitable uprights 12, the planes or wings being arranged so as to form upward and rearward dihedral angles. 60

By the use of the rearward dihedral angles, a greater range or shifting of the center of gravity of the machine may be obtained without affecting the longitudinal 65 stability of the machine.

The wings or planes 11 are of a single surface formation, with both faces constructed on the same curves, parallel and close together so that the entire wing will be thin and at the same time light, rigid 70 and strong in construction, that is to say, each of the wings embodies a body portion comprising a frame 13 having braces or ribs 14 incorporated therein and which ribs are parallel and extend across the frame, 75 and to the lower face of this frame, thus formed, a rigid wing surface 15 is secured. In order to produce such rigidity and at the same time produce a wing body which will not be distorted or change its form after 80 once being shaped, so as to always insure a maximum and uniform efficiency, the wings and surfaces are preferably of a veneer construction.

Each wing surface comprises a series of 85 laminæ, the outer laminæ being constructed preferably of tough paper or any other fibrous material, while the inner lamina is preferably constructed of fabric. All of these parts are firmly secured together by 90 suitable fastening means, such as glue, cement or the like, and result in a construction which possesses as nearly as possible, the rigidity of metal.

With this construction it will be manifest 95 that an effective and rigid surface wing may be produced and is more advantageous than a soft distortable surface, such as fabric or the like inasmuch as any soft or distortable surface by being distorted loses a greater 100 part of its efficiency.

The wings or planes are so shaped that an upward and forward pull will be exerted at the front of the wing, while the rear of the wing is shaped so that in conjunction with 105 the rearward dihedral angle thereof, the

action of the air on the rear portion of the wing will under certain conditions cause the wing to automatically aright itself. To accomplish this the front of the wing is shaped to preferably form a substantially 5 70 degree arc of a true circle as designated at 19, in Fig. 4, the chord 20 of this arc is of a length substantially equal to one fourth of the wing chord. From the end 21 of the 10 arc chord, the wing extends at a tangent and substantially straight, as at 22, to a distance substantially twice the length of the chord 20 of the arc 19, and terminates in a slight negative up-turned curve 23, forming a 15 rigid up-turned portion, the leading and trailing edges of the wing being rigid and all combined to produce an upward lift and forward pull representing the inherent tractor force of soaring birds and also im- 20 parting a self righting action to the wing. This structure also imparts to the wing a further and greater lifting capacity from the impact of the air currents on the under face of the tangent or straight portion 22 25 of the wing, while the negative curve 23 serves the function of balancing or automatically righting the wing.

It will be noted that by this construction of wing surface, there will be provided a 30 deep camber close to the leading edge of the wing on the under side thereof and which extends uniformly throughout the entire length of the wing, with the result that the air currents will be deflected upwardly at a 35 sharp angle. This will cause an area of low pressure or partial vacuum to be formed above and close to the leading edge of the wing, thereby causing the wing to be drawn or sucked in an upward and forward direction, thereby reducing to a minimum the 40 power or force necessary to propel the machine.

By virtue of the rearward dihedral angle of the wings, the entire upturned or negative rigid curved portions of the rear of the 45 wing stand back of the meta-center of the machine.

Should the propelling force for any reason fail, the machine, will by virtue of this 50 shape and arrangement of the wings, automatically assume a forward gliding angle and the machine will be drawn forwardly and downwardly by the force of gravity, with ever increasing speed until the pressure 55 of the horizontal air currents upon the rigid upturned rear portion of the wings, and ailerons which have by such action of the machine been elevated to be presented to a greater angle to the horizontal air currents, automatically depress the rear of the 60 wings, turning about the lateral axis of the machine, to elevate the leading edges of the wings, to cause the wings to be returned to a horizontal position.

55 The momentum gained by this gliding

action is expended in a forward and horizontal direction, and the above action is repeated until the machine reaches the ground.

The lateral stability or self righting effect is produced in the wings by the use of a 70 multiplicity of rigid vertical fins 24, which project or depend from the lower face of the wing and extend entirely across the plane surface in the direction of the path of flight, while at the same time they are 75 spaced laterally from each other in a direction longitudinally of the wing as shown more clearly in Fig. 2.

The lower edges of these fins may be straight or may be made to conform to the 80 contour of the wing.

These fins prevent the dangerous oscillation caused by the pressure of the wind rushing off or escaping alternately from the ends of the wings from the inside and 85 of the side gusts of air from the outside while rushing in under the wings, which would have a tendency to upset the machine.

The fins are so arranged that when the wings are tipped laterally, the lower extremity of each fin will terminate short of the lower extremity of the next adjacent fin on the side thereof adjacent the body of the machine.

These fins form obstructions for the side 95 gusts of air so that the air currents beneath the planes or wings will strike below the balancing point of the wings acting upon the fins to cause the planes or wings to be lowered instead of raised, thereby over- 100 coming the dangerous oscillation of the machine and the tendency of the side gusts of air to upset the machine. The fins also serve to increase the directional stability of the machine and prevent skidding or side-slipping of the machine during the turning 105 thereof.

The lateral stability or self righting action of the wings is obtained by these fins in conjunction with the short downwardly 110 curved portion at the top of the leading edge of the wings, as any sudden gusts of wind attacking the wing from the side, will, owing to the backward dihedral angle of the wing, strike the top of the downwardly 115 turned edge of the wing and will assist the fins in preventing the rising action of the wings.

Arranged below the upper wing, spaced for any desirable distance therefrom and disposed intermediate the upper and lower wings and on each side of the machine, adjacent the rear of the wings is an aileron designated generally by the reference numeral 25 having a slight upward curve at the rear 120 thereof, which curve is of substantially the same contour as the rear of the wing. This aileron is pivotally supported as at 26 and is adapted to be moved freely about the pivot 125 so as to raise its rear edge in any suitable 130

manner, preferably by means of a flexible member 27 secured thereto, which passes over a pulley 28 and is connected to a suitable controlling wheel 29, arranged in the 5 body of the machine.

In order to prevent the rear edge of the aileron from being moved below its normal horizontal position, any suitable stop device may be provided, such for instance as a 10 flexible member 30, one end of which is secured as at 31 to the aileron and the other end is anchored as at 32 to a fixed support. It will thus be seen that whenever it is desired to move the aileron about its pivot and 15 from the position shown in full lines to the position shown in dotted lines in Fig. 3, the operator actuates the controlling wheel 29, and it will also be seen that it is impossible for the rear edge of the aileron to move below the normal horizontal plane of the 20 aileron. This aileron is counterbalanced to permit of easy operation. By the provision of this aileron having a slight upward curve, a continued downward or negative pressure 25 at the rear or trailing end thereof will be maintained, and the ailerons by being stopped in their downward movement will be rigid. With this construction and arrangement of aileron, the outer or fast traveling wing or plane, in turning, will be unobstructed, that is, there will be no additional drag upon the wing as heretofore, thereby allowing the machine to turn on a 30 short curve or more level than heretofore. This is due to the fact that in turning, the inner aileron or the aileron adjacent to the point of turning is raised with respect to its wing to cause the air pressure to depress that wing, causing the high wing to 35 be unobstructed while the drag will be exerted on the inner or lower wing.

The body 10 of the machine is constructed to produce a limousine effect, the front end thereof being rounded and the rear being tapered laterally as shown more clearly in 40 Fig. 5.

The top and bottom of the body at the front end thereof are inclined toward each other as at 10^a and 10^b, as shown more clearly 45 in Fig. 6, for deflecting the air currents while the machine is in flight. The body is divided by means of a partition 33 into a passenger compartment 34 and a motor compartment 35. The partition 33 preferably 50 comprises swinging doors 36 so as to permit ready access into the motor compartment while in flight, and arranged within the passenger compartment 34 are seats 36, each of which is provided with a back 55 adapted to be folded as shown in Fig. 6. The motor compartment is provided with a partition 38 which supports the motor cylinders 39, the latter being superposed vertically and being provided with an outer 60 casing spaced from the cylinder proper and

having longitudinally disposed fins 40 arranged within the space between the motor cylinders and casing to form air passages extending lengthwise of the engine cylinder for cooling the same.

The compartment 35 is provided with air inlet openings 41 disposed to project below the bottom of the body so that outside air currents will enter the compartment 35.

The air passages formed by the fins 40 along the engine cylinders form the only source of communication between the chambers formed by the partition 38 in the engine compartment, so that the air currents entering the openings 41 will flow from one 75 of the chambers along the air passages of the engine cylinders into the other chamber and will be discharged through openings 42 which constitute the outlet passages from the other chamber.

A vertical shaft 43 is driven by the engine and the shaft is provided with a bevel gear 44, which meshes with a gear 45 secured to a horizontal shaft 46 of the propeller 47. This propeller 47 is located on the outside of 80 the body in the angle formed by the wings and adjacent the openings 42, and not only serves the purpose of propelling the machine, but operates to cause a suction through the openings 42 to induce the circulation of air into the openings 41 across the engine cylinders and out of the openings 42 to cool the engine.

The passenger compartment 34 is provided with doors 48 to permit ingress and 100 egress, and also windows 49.

What is claimed as new is:

1. A wing for aircrafts and the like, said wing having a rigid thin surface, the front portion of the wing describing substantially 105 a seventy degree arc of a true circle.

2. A single thin surface wing for aircrafts and the like, said wing forming an arc of a true circle at its forward edge to a point short of the center of the wing chord, the 110 rear edge of the wing terminating in a rigid negative curve, the intermediate portion of the wing being arranged at a tangent to the arc.

3. A single thin surface wing for aircrafts 115 and the like, said wing forming an arc of a true circle at its forward edge to a point short of the center of the wing chord, the rear edge of the wing terminating in a rigid negative curve, the intermediate portion of 120 the wing being arranged at a tangent to the arc, the said arc extending uniformly throughout the entire length of the wing.

4. A wing for aircrafts and the like, said wing having its body formed of a rigid thin 125 surface structure, the faces of the said surface being parallel, the front of the wing to a point short of the center of the wing chord, being shaped to form an arc of a true circle, and the rear of the wing short of the 130

center of the wing chord, being formed on a rigid curve opposite to the curve of the front of the wing, the portion of the wing intermediate the said curved portions being 5 arranged tangent to the arc at the front of the wing.

5. A wing for aircrafts and the like, said wing having its body formed of a rigid thin surface, the front of the wing for a distance 10 substantially one fourth of the wing chord being constructed to form an arc of a true circle, the portion of the body adjacent the arc being formed at a tangent to the arc for a distance substantially equal to twice the 15 length of the chord of the arc, and the rear of the wing adjacent such tangential portion of the arc being formed on a rigid negative curve.

6. A wing for aircrafts and the like, said 20 wing having its body formed of a rigid thin surface, the front of the wing for a distance substantially one fourth of the wing chord being constructed to form an arc of a true circle, the portion of the body adjacent the 25 arc being formed on a tangent to the arc for a distance substantially equal to twice the length of the chord of the arc, the rear of the wing adjacent such tangential portion and for substantially a distance equal to the 30 chord of the arc being formed on a rigid negative curve, and a curved aileron pivotally arranged in a plane different from the plane of the wing and coöperating with the wing.

35 7. A wing for aircrafts and the like, said wing having its body formed of a rigid thin surface, the front of the wing for a distance substantially one fourth of the wing chord being constructed to form an arc of a true 40 circle, the portion of the body adjacent the arc being formed on a tangent to the arc for a distance substantially equal to twice the length of the chord of the arc, the rear of the wing adjacent such tangential portion 45 and for substantially a distance equal to the chord of the arc being formed on a rigid negative curve, and a counterbalanced and curved rigidly constructed aileron pivotally arranged in a plane different from the plane 50 of the wing and coöperating with the wing.

8. A wing for aircrafts and the like, said wing having its body formed of a single rigid surface, the rear edge of said wings being formed in a rigid negative curve, and 55 a counterbalanced upwardly curved and rigid aileron adjacent said edges spaced

from and disposed in a plane different from the plane of the wing and coöperating with the said wing.

9. A wing for aircrafts and the like, said 60 wing having its body formed of a single rigid surface, the rear edge of said wings being formed on a rigid negative curve, a counterbalanced aileron adjacent said edges spaced from and disposed in a plane different from the plane of the wing and coöperating 65 with the said wing and a stop for limiting the downward movement of the outer end of the aileron.

10. The combination of spaced superposed 70 wings, the rear edges of the wings being formed on a rigid negative curve, and a pivotally mounted upwardly curved and rigid aileron disposed adjacent said edges intermediate and spaced from both of said wings. 75

11. The combination of spaced superposed wings, a pivotally mounted upwardly curved rigid aileron disposed intermediate and spaced from both of the wings, and means 80 operating as a stop for holding the aileron against movement below a substantially horizontal plane.

12. A wing for aircrafts and the like, said wing having a rigid thin surface, the front portion of the wing adjacent the leading edge describing an arc of a true circle, the rear of the wing describing a rigid negative curve, the intermediate portion of the wing being straight and arranged at a tangent to the arc, and fins depending below the lower 90 face of the wing and spaced laterally in a direction lengthwise of the wing.

13. A wing for aircrafts and the like, said wing having a rigid thin surface, the front portion of the wing adjacent the leading edge describing an arc of a true circle, the rear of the wing describing a rigid negative curve, the intermediate portion of the wing being straight and arranged at a tangent to the arc, and rigid fins depending below the 100 lower face of the wing in the direction of flight of the wing, said fins extending entirely across the wing face and being spaced laterally from each other.

In testimony whereof I have signed my 105 name to this specification, in the presence of two subscribing witnesses, on this 6th day of March, A. D. 1917.

THOMAS P. BROOKE.
